(57) **CLAIM**

We claim the ornamental design for a camera stabilizer, as shown and described.

DESCRIPTION

FIG. 1 is a front perspective view of a camera stabilizer according to a first embodiment of the present invention.

FIG. 2 is a rear perspective view of the camera stabilizer of FIG. 1.

FIG. 3 is a front view of the camera stabilizer of FIG. 1.

FIG. 4 is a rear view of the camera stabilizer of FIG. 1.

FIG. 5 is a left-side view of the camera stabilizer of FIG. 1.

FIG. 6 is a right-side view of the camera stabilizer of FIG. 1.

FIG. 7 is a top view of the camera stabilizer of FIG. 1.

FIG. 8 is a bottom view of the camera stabilizer of FIG. 1.

FIG. 9 is a front perspective view of the camera stabilizer of FIG. 1 having an arm thereof extended.

FIG. 10 is a rear perspective view of the camera stabilizer of FIG. 9.

FIG. 11 is a top perspective view of the camera stabilizer of FIG. 9.

FIG. 12 is a bottom perspective view of the camera stabilizer of FIG. 9

FIG. 13 is a front view of the camera stabilizer of FIG. 9.

FIG. 14 is a rear view of the camera stabilizer of FIG. 9

FIG. 15 is a left-side view of the camera stabilizer of FIG. 9.

FIG. 16 is a right-side view of the camera stabilizer of FIG. 9.

FIG. 17 is a top view of the camera stabilizer of FIG. 9.

FIG. 18 is a bottom view of the camera stabilizer of FIG. 9; and,

FIG. 19 is a front perspective view of the camera stabilizer of FIG. 9 stabilizing an unclaimed camera device.

The broken lines illustrate portions of the camera stabilizer that form no part of claimed design.
